ATTORNEY.

UNITED STATES PATENT OFFICE.

LOUIS COLELLA, OF DETROIT, MICHIGAN.

RUBBER SOLE.

Application filed October 19, 1921. Serial No. 508,715.

To all whom it may concern:

Be it known that I, LOUIS COLELLA, a subject of the King of Italy, residing at Detroit, in the county of Wayne and State 5 of Michigan, have invented a certain new and useful Improvement in Rubber Soles, of which the following is a specification.

My invention relates to a new and useful improvement in a rubber sole and has 10 for its object the provision of a rubber sole to be temporarily attached to a shoe which will be simple of structure, economic of manufacture and highly efficient in use.

Another object is the provision of a rubber sole which may be temporarily attached to a shoe and which will be so constructed as to afford an absolutely watertight connection with the shoe and provide a waterproof sole for the shoe.

Another object is the provision in a rubber sole of metallic spring retaining members which will serve to retain the sole in position on the shoe.

Other objects will appear hereinafter.

The invention consists in the combination and arrangement of parts hereinafter described and claimed.

The invention will be best understood by reference to the accompanying drawings 30 which form a part of this specification and in which,

Fig. 1, is a side elevational view of the invention, showing it attached to a shoe,

Fig. 2, is a top plan view of the invention,

Fig. 3, is a sectional view taken on line 3—3 of Fig. 2,

Fig. 4, is a perspective view of the spring clip used in the invention,

Fig. 5, is a sectional view taken on substantially line 5—5 of Fig. 2.

The invention is designed to provide a rubber sole which may be slipped over the sole of a shoe and temporarily attached thereto so as to provide a waterproof sole which may be easily removed and which will be so attached as to prevent its removal from the shoe while the same is being worn. It comprises a main sole portion 8 which is preferably constructed from rubber or some other waterproof material. Projecting upwardly from this sole portion, at right angles thereto, is a flange portion 9, projecting inwardly from which, at the upper end thereof, is a flange forming portion 10. Projecting upwardly from this portion, at right angles thereto,

is a flange forming portion 11. All of these flange forming portions are at right angles to the portion from which they project and are preferably formed from rubber. Embedded in the portions 8, 9, and 10 adjacent the shank of the device, at opposite sides of the sole-forming portion 8 are spring metallic clips or retaining members 12, each of which is provided with a slot 13 through which the rubber of the sole will flow when the clips are embedded in position, it being preferable that these clips be mounted in position during the molding of the sole. Each of these clips is provided, adjacent one end with an upwardly, angularly extending portion 14 from which projects an upwardly, inwardly extending portion 15. At the opposite end of these clips there projects an angularly downwardly extending member 16. It will be noted that the portions 8 and 10 together with the portion 9 form a sort of passage or channel. In assembling the sole on a shoe the sole of the shoe 7 is engaged in the passage 17 and the device is then forced rearwardly onto the shoe, the sole of the shoe, as it passes along the passage, forcing the rubber sole to stretch and spread at the narrow portion or shank. As the sole of the shoe passes into place the rubber sole returns to its former shape and securely binds the shoe. The portion 10 engages the upper surface of the extending edge of the shoe sole and fits snugly thereto. The portion 11 engages the lower portion of the upper of the shoe and fits snugly thereto so that no water may flow from the upper of the shoe into the passage 17. The clips serve as a reinforcement of that portion of the rubber sole which is subjected to the greatest wear when the sole is being placed on the shoe and removed therefrom. The portion of the clips which is embedded in the portion 8, 9 and 10 of the rubber sole serve to retain these portions in close engagement with the shoe at all times. The downwardly turned portion 16 serves to prevent any movement of the main body of the clip in the portion 8, thereby assisting the rubber which has flowed through the opening 13 to resist longitudinal thrusts. The device is removed from the shoe in the reverse manner to the way it is put on. It is necessary that forwardly directed pressure be applied to the rear portion of the sole 8.

It is also to be noted that the shank of

the invention is turned upwardly from the plane of the main body of the sole so that a snug engagement is provided for at the arch of the shoe. In this way I have provided a rubber over-sole which affords the greatest protection against moisture and at the same time is neat in appearance. I have also reduced to a minimum the probability of the sole coming loose from the shoe 10 while being worn.

While I have illustrated the preferred form of construction I do not wish to limit myself to the precise detail of structure set forth but desire to avail myself of all the 15 modifications and changes which come within the scope of the appended claims.

Having thus described my invention what I claim as new and desire to secure by Letters Patent is:

20 1. A retaining clip for a removable sole comprising a longitudinal metallic body portion having an elongated slot formed therein; a double angularly turned portion ad-

jacent one end of said body portion; and an angularly turned integral portion adjacent the opposite end of said body portion, said double angularly turned portion being adapted for engaging the side of a sole for retaining the removable sole thereon. 25

2. A retaining clip for a removable sole 30 comprising a main body portion having an elongated slot formed therein; an angularly turned portion adjacent one end of said main body portion and integral therewith; an angularly turned portion adjacent 35 the end of said angularly turned portion, said portions being adapted for gripping the sole with which used; and an angularly oppositely turned portion adjacent the opposite end of said main body portion, for 40 anchoring the same to said removable sole.

In testimony whereof I have signed the above and foregoing specification at Detroit, Michigan.

LOUIS COLELLA,
